APPLIANCE WITH BUILT-IN STORAGE
COMPARTMENTLawrence R. Collins, Louisville, Ky., assignor to General
Electric Company, a corporation of New York
Filed Oct. 7, 1963, Ser. No. 314,187
4 Claims. (Cl. 312—223)

This invention relates to appliances, and more particularly to appliances having controls for determining the operation thereof and which further include a built-in storage compartment.

In carrying out my invention in one form thereof, I provide an appliance wherein components which cooperate to perform a useful function on articles are disposed within a cabinet having a substantially flat top surface, the surface having an opening formed therein for access into the cabinet. A control panel assembly is positioned substantially above the top surface, and supports manually operable control means for determining operation of the components at the will of the operator. The panel assembly is supported by back and side vertical walls which extend up from the top surface behind the access opening. A door is so disposed that it cooperates with the vertical walls to form a storage compartment behind the opening thereby providing effective storage utilization of the space between the top surface and the control panel assembly by the same members which support the control panel assembly.

In a preferred embodiment of my invention, the control panel assembly extends forward slightly from the supporting vertical walls, and a lamp is disposed so as to shine down from the bottom surface joining the bottom of the panel assembly to the vertical walls. By so positioning the panel assembly and the lamp, a substantial amount of light is provided, both for the interior of the storage compartment and within the appliance cabinet through the access opening.

The subject matter which I regard as my invention is particularly pointed out and distinctly claimed in the concluding portion of this specification. My invention, however, both as to organization and method of operation together with further objects and advantages thereof, may best be understood by reference to the following description taken in conjunction with the accompanying drawings.

In the drawings, FIGURE 1 is a fragmentary side elevational view, partly broken away, of an appliance (specifically a washing machine) incorporating my inventive concept; and

FIGURE 2 is a fragmentary view in perspective of the machine of FIGURE 1.

Referring now to the figures, there is provided an appliance, specifically a washing machine 1 in this case, wherein an outer cabinet 2 has a top surface 3 formed with an access opening 4 closable by a lid 5. Within the cabinet there are supported the various conventional components which together provide an operative automatic washing machine as is well known in the art.

While these are not shown in any great detail, since their particular structure is not part of my invention, they may include a perforated clothes-containing basket 6 mounted within an imperforate liquid-retaining tub 7. Liquid may be provided into the tub and basket through a water outlet 8, and the passage of water from this outlet is controlled by an appropriate valve 9 having electrical control components 10. Within the basket there may be provided an appropriate washing mechanism such as an agitator 11. It will be understood that a suitable electrical means, such as a motor and an appropriate transmission (not shown), are provided so as to cause

2

washing motion of the agitator 11 when liquid and clothes are provided within basket 6 and tub 7, and so as to spin out the liquid from the clothes by high speed rotation of basket 6.

5 Normally, automatic washing machines follow an automatic sequence, first washing the clothes and then spinning wash liquid out of them, then rinsing the clothes, and then finally spinning the rinse liquid out. After this, such machines normally shut themselves off. In order to initiate a desired sequence of operation, such machines are conventionally provided with appropriate manual controls. In this case, the manual control is shown at 12, and it will be seen that it is disposed behind the access opening 4 and a substantial distance above the top surface 3 for convenience. Manual member 12 may operate through a conventional sequence control mechanism 13 to control the various electrical components of the machine, including both those which are not shown and those which are shown such as the valve control elements 10.

In order to support control element 12 and sequence control 13 at the desired height above surface 3, I provide side supporting walls 14 and 15 and a rear supporting wall 16, all extending upwardly from the flat surface 3. The control panel assembly 17 is secured in any desired manner on these supports so as to be rigidly secured thereabove. Preferably, as shown, the front of the control panel assembly extends forwardly from the main portion of the vertical wall so that there is formed a bottom surface 18. This bottom surface is formed as a transparent glass pane 19 behind which is positioned a suitable lamp 20. In the present case, lamp 20 is of the fluorescent type, extending substantially across between walls 14 and 15, although, of course, conventional incandescent lamps could be used equally effectively.

Pane 19 is supported on part of a supporting member 21 which extends across between the two walls 14 and 15 and is secured thereto. Member 21 also cooperates with a bottom member 22 to provide guides for a pair of sliding doors 23. Doors 23 are so formed that they may be moved to a position where they form an enclosing compartment 24 with walls 14, 15 and 16. In this manner the supporting walls 14, 15 and 16 for the control panel provide the additional function of forming a storage compartment which is readily and conveniently accessible to an operator of machine 1. In the case of a washing machine, as illustrated, it will readily be seen that bleaches, bluing, small boxes of detergents, and the like, may very conveniently be stored in compartment 24. In addition, it will be seen that the structure provides a relationship of parts whereby lamp 20 illuminates the storage compartment when it is opened, and also shines directly through the access opening 4 of machine 1 so as to illuminate the interior thereof. If so desired, an enclosed channel 24a (FIGURE 2) may be provided for the passage of the necessary electrical conductors from the control panel 17 to the main part of machine 1.

The control panel assembly also includes a member 25 which is hingedly secured at 26 on the rear wall 16. The normal position of member 25 is that shown in solid outline in FIGURES 1 and 2, wherein it provides a closure for enclosing the sequence control mechanism. In order to open member 25 to the position shown in dotted outline in FIGURE 1, it is merely necessary to remove the various control knobs which protrude through the appropriate openings in member 25. As soon as this is done, the sequence control assembly 13 and the lamp 20 are immediately accessible for servicing. This is particularly desirable in the case of the lamp 20 since such articles often have a normal life shorter than that of the

appliance with which they are associated, and need to be replaced at various times.

My invention thus provides an assembly of parts readily accessible to a person operating machine 1, while at the same time the supporting structure provides storage space, and the overall relationship of the parts permits a single light source to be used both for the storage space and for the interior of the appliance through the access opening.

While in accordance with the patent statutes I have described what at present is considered to be the preferred embodiment of my invention, it will be obvious to those skilled in the art that various changes and modifications may be made therein without departing from the invention, and it is therefore aimed in the appending claims to cover all such equivalent variations as fall within the true spirit and scope of my invention.

What I claim as new and desire to secure by Letters Patent of the United States is:

1. An appliance comprising:

- (a) a cabinet having a substantially flat top surface with an opening formed therein for access into said cabinet;
- (b) a plurality of components within said cabinet for cooperatively providing a useful function on articles placed in said cabinet through said opening;
- (c) manually operable control means for said components;
- (d) a control panel assembly substantially above said top surface supporting said control means;
- (e) back and side vertical walls extending up from said top surface behind said opening and supporting said control panel assembly;
- (f) and a door behind said opening forming a storage compartment with said back and side vertical walls thereby to provide effective storage utilization of the space between said top surface and said control panel assembly.

2. The appliance defined in claim 1 wherein said control panel includes an electric lamp positioned to shine downwardly thereby to provide light both for said compartment and for the interior of said cabinet through said access opening.

3. An appliance comprising:

- (a) a cabinet having a substantially flat top surface with an opening formed therein for access into said cabinet;
- (b) a plurality of components in said cabinet for cooperatively providing a useful function on articles placed in said cabinet through said opening;
- (c) manually operable control means for said components;
- (d) a control panel assembly substantially above said top surface supporting said control means;
- (e) back and side vertical walls extending up from said top surface behind said opening and supporting said control panel assembly, said control panel assembly extending forward from said vertical walls and having a bottom surface joining it to the fronts of said vertical walls, said bottom surface being formed at least in part of transparent material;
- (f) a lamp positioned to shine through said part of transparent material thereby to cast light downwardly;
- (g) and a door behind said opening forming a storage compartment with said back and side vertical walls thereby to provide effective storage utilization of the space between said top surface and said control panel assembly, said lamp providing illumination both for said compartment and into said access opening.

4. The apparatus defined and claimed in claim 3 wherein in the top of said control panel is hingedly mounted on said vertical walls and is movable from an operative closed position to an open position providing access to said light therein.
